UNITED STATES PATENT OFFICE.

HARRY C. ALLEN, OF CHARLOTTE, NORTH CAROLINA.

SLUG GUIDE.

Application filed February 4, 1924. Serial No. 690,547.

To all whom it may concern:

Be it known that I, HARRY C. ALLEN, a citizen of the United States, residing at Charlotte, in the county of Mecklenburg and 5 State of North Carolina, have invented a new and useful Slug Guide, of which the following is a specification.

This invention relates to slug guides for type-setting machines.

10 As is well known to those skilled in the art slugs for type-setting machines are cast in different lengths and are designed to gravitate along an upright guide in transit from the casting mechanism to the galley.

15 The object of the invention is to provide a simple and efficient device which will prevent the upper end of the slug, as it moves down the chute of the type-setting machine onto the galley, from tipping forward and there- 20 by transposing when it reaches the galley.

Another object is to provide a device of 25 this character made adjustable to adapt it for use with slugs of different lengths and which is equipped with spring means for holding it in adjusted vertical position to 30 locate it with reference to a slug to pass thereby and also to permit it to yield laterally to release slugs should they become clogged in the machine, the spring means thus performing a double function.

With the foregoing and other objects in view which will appear as the description proceeds, the invention resides in the combination and arrangement of parts and in 35 the details of construction hereinafter described and claimed, it being understood that changes in the precise embodiment of the invention herein disclosed, may be made within the scope of what is claimed without departing from the spirit of the invention.

40 In the accompanying drawings:—

Figure 1 represents a perspective view of the attachment constituting this invention shown applied, the parts of the type-setting 45 machine which constitute no part of the invention being shown in dot and dash.

Fig. 2 is a transverse section through the head constituting a part of the attachment; and

50 Fig. 3 is a similar view taken on the line 3—3 of Fig. 1.

In the embodiment illustrated the attachment constituting this invention is designed to be mounted on the right hand knife guide plate 1 by means of screws passing through said plate and through a plate 19 which con-

stitutes a part of the attachment. The plate 19 is designed to equalize the thickness of the knife block slug plate when the slug is ejected through the knives so that it will 60 be directed into the path of the roller 17 constituting a part of the attachment.

The plate 1 constitutes a part of the bracket 2 of a type-setting machine in which is located a chamber or chute 5 for the passage of the slugs, not shown. The chute 5 guides the slugs to the galley 3 and the slugs are pushed sidewise along the galley by a vibratory lever 4.

The attachment comprises a rod 10 mounted on the outer face of plate 1 by means of brackets 11 in which the rod is held by screws 12. A head 13 is mounted to slide longitudinally and to swing or pivot laterally on said rod for a purpose presently to be 70 described. A finger 14 made integral with the head projects at one end beyond one face of the head and has engaged therewith one end of a coiled spring 18 which is wound around the rod 10 adjacent the head and 75 bears at its other end against plate 1. This spring operates to hold the head in adjusted position on rod 10 and also to permit it to yield laterally or rather to pivot on the rod so that it may yield should slugs become 80 clogged in the guide 5.

An arm 15 extends laterally from the head 13 and has a pintle 16 projecting at right angles from the inner face of its outer end. A fiber roller 17 is mounted on 90 the pintle 16 and is located over the guide 5 in the path of the slugs passing through the guide for engaging the front type edges of the slugs and holding them against forward tilting movement or overturning in 95 transit through the upright portion of the guide or bracket thereby causing the slugs to gravitate to the galley with their type edges uppermost.

In the use of this attachment the plate 19 is fastened to the knife plate 1 on the side opposite to that which carries rod 10 and this plate 19 operates to equalize the thickness of the knife block slug plate so that when the slug is ejected through the knives 100 the type carrying edge thereof will hit true against the fiber roller 17 which extends transversely across the upper portion of chute 5. The head 13 is adjustable on rod 10 to adapt it for use in connection with 105 slugs of different lengths, the coiled spring 18 being designed to hold the head in ad- 110

justed position. This spring 18 also exerts its tension to hold the head with the arm or roller 17 thereof in operative position across the slug chute and should the chute 5 become clogged with slugs this spring will permit the roller to be moved outwardly and the head to pivot on rod 10 to release the slugs.

From the above description it will be obvious 10 that this attachment is simple and cheap to manufacture and may be readily installed on any type-setting machine and should any of the parts become broken or worn they may be easily replaced.

15 I claim:—

1. In a slug guide for type-setting machines, an arm, a pivot for mounting said arm, a spring mounting for holding said arm in adjusted vertical position to locate 20 it with reference to a slug, to pass thereby, and to permit said arm to yield to release said slugs should they become clogged in the type-setting machine.

2. A slug guide for type-setting machines 25 comprising a vertically movable head having a laterally extending arm with a roller projecting at right angles therefrom, spring means for holding said head in adjusted vertical position to locate it with reference to a slug to pass thereby and to permit it to 30 yield to release slugs should they become clogged in the type-setting machine.

3. The combination with the knife plate 35 of a type-setting machine; of spaced brackets mounted on said plate, a rod secured in said brackets, a head slideable and rotatable on said rod with an arm extending laterally therefrom, a roller projecting

at right angles from said arm and adapted to be located over a slug chute, and spring 40 means for holding said head in adjusted vertical position on said rod and to permit the head to yield to release slugs should they become clogged in the type-setting machine.

4. The combination with the knife plate 45 of a type-setting machine; a rod mounted on said plate, a head slideable and rotatable on said rod with an arm extending laterally therefrom, a roller projecting at right angles from said arm and adapted to be located over a slug chute, said head having a finger projecting beyond one end thereof, and a spring coiled on said rod with one end engaged with said finger and the other bearing 55 against said knife plate whereby the head is held in adjusted vertical position and permitted to yield should the type-setting machine become clogged with slugs.

5. The combination with the knife plate 60 of a type-setting machine; of a rod mounted on one face of said plate, and an equalizing plate on the other side, an arm mounted to slide and pivot on said rod, and spring means for holding said arm in adjusted vertical position to locate it with reference to a 65 slug to pass thereby, and to permit said arm to yield to release said slugs should they become clogged in a type-setting machine.

In testimony that I claim the foregoing as my own I have hereto affixed my signature in the presence of two witnesses.

HARRY C. ALLEN.
